UNITED STATES PATENT OFFICE

LAWRENCE J. GAGNON, OF CLEVELAND, OHIO

DESIGN FOR A LAMP

Application filed April 13, 1932. Serial No. 43,489. Term of patent 3½ years.

To all whom it may concern:

Be it known that I, LAWRENCE J. GAGNON, a citizen of the United States, residing at Cleveland, in the county of Cuyahoga and State of Ohio, have invented a new, original, and ornamental Design for a Lamp, of which the following is a specification, reference being had to the accompanying drawing, forming part thereof:

In the drawing, Fig. 1 is a front elevation of the lamp showing the lamp shade in vertically suspended position, and Fig. 2 is a side elevation of the lamp showing the shade in slightly inclined but suspended position.

I claim:

The ornamental design for a lamp as shown and described.

LAWRENCE J. GAGNON.
